(57) **CLAIM**

The ornamental design for a vehicle fender, as shown and described.

DESCRIPTION

FIG. 1 is a top left front perspective view of a left vehicle fender. The novel design also includes a right vehicle fender which is mirror symmetrical to the fender shown in FIGS. 1-9, and is therefore not separately illustrated.

FIG. 2 is a top left rear perspective view thereof;

FIG. 3 is a top right rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

1 Claim, 9 Drawing Sheets
